COMPASS ALARM

John Hays Hammond, Jr., Gloucester, Mass.

Application February 17, 1936, Serial No. 64,207

1 Claim. (Cl. 33—222)

This invention relates to navigational instruments and more particularly to an improved system for automatically giving a warning when the vessel deviates from a given course.

More specifically the invention provides a system in which an alarm is automatically sounded when the vessel deviates more than a predetermined number of degrees from a set course for a definite interval of time.

An object of the invention is to provide a practical, dependable, and efficient system of the type above indicated.

Various other objects and advantages will be apparent as the nature of the invention is more fully disclosed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is a top plan view of the instrument with the casing removed and with the associated electrical circuits indicated diagrammatically, and

Fig. 2 is a sectional elevation of the instrument taken on line 2—2 of Fig. 1.

In the following description and in the claim parts will be identified by specific names for convenience, but they are intended to be as generic in their application to similar parts as the art will permit.

Referring more particularly to the accompanying drawings, a binnacle casing 10 is mounted on the bridge or other suitable location on the vessel. A gimbal ring 11 is mounted in the casing 10 on pivots 12 and ring 13 is pivotally mounted in the gimbal ring 11 by means of pivots 15.

Secured to the ring 13 is a second ring 16 on which is mounted a circular frame 17. Mounted in the frame 17 is a compass bowl 18 which is made of transparent material such for example as glass.

Over the top of the bowl 18 is mounted a circular glass plate 19 which is held in position by means of ring 21. Mounted in the bowl 18 is a pivot 22, on the point of which is rotatably mounted a compass card 23 which may be of well known and standard construction. Attached to the compass card 23 directly below the north point thereof is a rectangular mirror 25, the width of which only extends a few degrees on either side of the north point of the compass. At the opposite side of

the compass card 23 is located a counterweight 26 for balancing the weight of the mirror 25.

Rotatably mounted between the ring 16 and the frame 17 is a second bowl 30. The upper edge of this bowl is inclined as shown at 31 and is engraved with the points of the compass as shown in Fig. 1. A segmental hole 32 is cut through the frame 17 so as to expose to view the points of the compass engraved on the surface 31. A rubber line 33 is engraved on the frame 17 on the longitudinal line of the vessel.

Secured to the outside of the bowl 30 is a commutator 35 made of insulating material in which are mounted three slip rings 36, 37, and 38. Below the commutator 35 and secured to the bowl 30 is a beveled gear 39 with which meshes a beveled pinion 40. This pinion is secured to one end of a shaft 41, which is rotatably mounted in a bracket 42 forming part of the ring 13. A knurled knob 43 is secured to the other end of the shaft 41. A spiral compression spring 45 surrounds the shaft 41 between the pinion 40 and the bracket 42, thus locking the pinion 40 against the gear 39 to keep the latter from turning due to vibration, etc. A hinged door 46 is provided in the casing 10 in order to permit access to the knurled knob 43.

The slip rings 36 and 37 are connected to a lamp 47 which is mounted in the bowl 30. The light from this lamp is focused by means of a lens 30 system 48 into a beam 49. This beam of light is reflected from a mirror 50 onto the mirror 25, mounted on the compass card 23. From the mirror 25 the beam of light is reflected by two mirrors 51 and 52 onto a photo-electric cell 53. This cell may be of the type known as a photronic cell manufactured by the Weston Electrical Instrument Company which does not need a source of power for its operation. The photo-electric cell 53 is connected to the two slip rings 37 and 38.

The three slip rings 36, 37, and 38 are engaged by three brushes 55, 56, and 57 which are mounted on a block of insulating material 58 which is secured to the ring 13. The three brushes 55, 56, and 57 are connected to a three conductor cable 62 having conductors 59, 60, and 61 (Fig. 1). This cable passes from the block of insulating material 58 along the under surface of the gimbal ring 11 and passes out through the casing 10. The conductor 59 is connected through a switch 63 to one side of a source of alternating current 65, the other side of this source being connected to the conductor 60. The conductor 60 is connected by a branch conductor 66 to one side of the winding of a sensitive relay 67, the

other side of the winding of which is connected to the conductor 61.

The armature of the relay 67 is connected through a switch 68 to one side of the winding of a solenoid 69, the other side of the winding of which is connected through a battery 70 to the back contact of the relay 67. The solenoid 69 is provided with a core 71 to which is secured a collar 72. Between the collar 72 and the solenoid 69 is a spiral compression spring 73 which tends to hold the core 71 in its outmost position. Secured to the upper end of the core 71 is a piston 75 which reciprocates in a cylinder 76. This cylinder is provided with a large port 77 and a small port 78. A valve 79 is mounted over the large port 77.

Secured to the core 71 is an arm 81 of insulating material to which is attached a block 82 of conducting material. Located in the path of travel 20 of the block 82 are two contacts 85 and 86, the former being connected to one side of a battery 87 and the latter through a switch 88 to a lamp 89 and through a switch 90 to a bell 91. The return circuits from the lamp 89 and the bell 91 25 are connected to the other side of the battery 87.

In the operation of the form of the invention just described, after it is determined upon which course the vessel is to proceed, the door 46 in the binnacle casing 10 is opened and the knurled knob 30 43 is turned so as to cause rotation of the bowl 30 by means of the pinion 48 and the gear 39 until the desired course as shown by the compass scale engraved on the surface 31 registers with the lubber line 33. In the case shown in the accompanying figures, the desired course is due north so that this point registers with the lubber line 33. The helmsman then steers the vessel so that it is heading due north as indicated by the compass card 23. At this time the mirror 25 on the under 35 surface of the compass card 23 will be in line with the optical system carried in the bowl 30 so that light from the lamp 47 will impinge upon the photo-electric cell 53, thus energizing this cell which in turn will cause the energization of the sensitive relay 67.

The switch 68 is then closed and either or both of the switches 88 and 90 are closed as desired. As long as the vessel remains on the predetermined course, in this case due north, the sensitive relay 50 67 will remain energized thus preventing the energization of the solenoid 69. If, however, the vessel deviates more than a predetermined number of degrees from this course, the mirror 25 will move out of line with the optical system, thereby shutting off the light to the photo-electric cell 53 which in turn will cause deenergization 55 of the sensitive relay 67. This in turn will close the circuit through the solenoid 69, thus causing the core of this solenoid to be moved slowly downward at a rate which is determined by the amount of air entering the port 78.

If the vessel remains off its course for a predetermined interval of time, the conducting block 65 82 will engage the contacts 85 and 86, thereby closing the circuits through the light 89 and bell 91, which will cause a visible and audible signal to be produced, thus warning the helmsman and the captain of the vessel that the proper course is not being maintained. This signal will con-

tinue until the vessel is returned to its proper course, at which time the mirror 25 will again be in line with the optical system so that the photo-electric cell 53 will be again illuminated. This will energize the relay 67, thereby deenergizing the solenoid 69. When this occurs, the core 71 will be moved rapidly upwards under the action of the spring 73 and due to the air freely passing out of the large port 77. The variation in azimuth required to interrupt the light beam 10 is determined by the characteristics of the mirror 25 which may be designed to cause actuation of the warning signal after any desired angular deviation.

If the vessel deviates from its predetermined 15 course sufficiently to energize the relay 67 but is returned to the course before the core 71 of the solenoid 69 has moved sufficiently to cause the engagement of the contacts 85 and 86 by the conducting block 82, the relay 67 will be de- 20 energized thereby allowing the core 71 to move rapidly upward to its initial position without causing the alarm to be sounded.

Though only two forms of alarm have been shown in this invention, it is to be understood 25 that it is not limited thereto, but any suitable number or type of systems may be employed which may be located at any part of the ship such as in the captain's cabin or elsewhere to apprise the captain or other officers of the vessel 30 that the proper course is not being maintained.

It is to be understood that any desired control mechanisms such as a steering control may be substituted for the alarm or may be connected to the battery 87 in addition to the alarm signals 35 set forth. The circuits disclosed are merely illustrative of various control devices that can be actuated in response to a predetermined variation in azimuth of the vessel.

Although only a specific embodiment of the 40 invention has been shown herein, it is to be understood that the invention is not limited to any specific construction but may be embodied in various forms without departing from the spirit of the invention or the scope of the appended claim. 45

What is claimed is:

In a navigational system, a housing, a compass card movable with respect thereto to indicate direction, a photoelectric system carried by said housing comprising a light source, a photoelectric cell and means carried by said compass card to focus light from said source onto said cell in a predetermined position of said housing relatively to said card, means to rotate said housing to a predetermined position to correspond with the desired course, a normally open signal circuit, a retarded electromagnetic means for closing said signal circuit when energized for a given time interval, an energizing circuit for said electromagnetic means, a relay biased to normally close said energizing circuit, and means controlled by said photoelectric cell to hold said relay open when said light is focused thereon by said compass card, whereby said signal circuit is energized only in response to a deviation of said housing relatively to said card in either direction by more than a given angle and for said given time interval.
